(57) CLAIM

I claim the ornamental design for a monument, as shown and described.

DESCRIPTION

FIG. 1 is a perspective view of the monument; FIG. 2 is a front view of the monument, the back view being a mirror image thereof;

FIG. 3 is a right side view of the monument, the left side view being a mirror image thereof;

FIG. 4 is a top view of the monument; and,

FIG. 5 is a bottom view of the monument.

The broken-line features shown in the drawings form no part of the claimed design.
